CLAIM

The ornamental design for an uninterruptible power supply, as shown and described.

DESCRIPTION

FIG. 1 is a perspective view of an uninterruptible power supply design of an embodiment of the present disclosure;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a back elevational view thereof;

FIG. 8 is a perspective view of an uninterruptible power supply design of another embodiment of the present disclosure;

FIG. 9 is a top plan view thereof;

FIG. 10 is a bottom plan view thereof;

FIG. 11 is a left side elevational view thereof;

FIG. 12 is a right side elevational view thereof;

FIG. 13 is a front elevational view thereof; and,

FIG. 14 back elevational view thereof.

The broken lines shown represent unclaimed subject matter and form no part of the claimed design.
